MARK B. WHITE, OF HANOVER, ILLINOIS.

WINDING-MACHINE.

1,290,447.

Specification of Letters Patent.

Patented Jan. 7, 1919.

Application filed February 27, 1918. Serial No. 219,412.

To all whom it may concern:

Be it known that I, MARK B. WHITE, a citizen of the United States, and a resident of Hanover, in the county of Jo Daviess and 5 State of Illinois, have invented certain new and useful Improvements in Winding-Machines, of which the following is a description, reference being had to the accompanying drawings, which form a part of my 10 specification.

My invention relates to mechanism for winding the twisted yarn or thread, as it comes from the twisting mechanism, immediately upon bobbins which are so operated 15 as to maintain the proper twist of the yarn as it is discharged by the twisting head or mechanism, thus providing a finished yarn ready for use on the looms and in the warping department.

20 The object of my invention is to provide mechanism whereby the finished yarn or thread will be properly wound on the bobbins; the winding of the yarn being automatically controlled, as will be more fully 25 comprehended from the following detailed description of the accompanying drawings, wherein:—

Figure 1 is a plan view of the winding mechanism or unit with portions of the supporting frame or members broken away.

Fig. 2 is a partial side elevation and sectional view of the mechanism, as disclosed in Fig. 1.

Fig. 3 is a detail view in plan of the yarn-controlling device of the mechanism, with the top plate or cover removed.

Fig. 4 is a detail view in side elevation of the yarn-controlling device shown in Fig. 3, and as illustrated in Fig. 2.

40 Fig. 5 is a bottom plan view of the yarn-controlling mechanism, the bobbin-supporting spindle and supporting rods or frame being broken away.

Fig. 6 is a detail view, in perspective, of 45 one of the movement-controlling members.

Fig. 7 is a vertical sectional view taken on the line 7—7 of Fig. 4 looking in the direction of the arrows.

In practice, with my improved twisting 50 and winding mechanisms or units, the units are usually arranged in batteries; the twisting units and the winding units in my improved machine being correlated or arranged in juxtaposition and all the units preferably 55 driven from a common drive shaft, which may be provided with graduated or stepped

pulleys in order to permit the speed of the different units to be varied, commensurate with the speed of delivery from the carding machines to the respective units. The 60 method of driving from a common driver or shaft may be the same as the method at present in use; and as it forms no part of the present invention, the same has not been illustrated and need not therefore be described.

As the different units of the winding mechanism are all identical in construction and operation, a single unit is merely illustrated, with portions of a suitable supporting frame shown. The yarn discharged from the twisting heads or units is passed through the hollow hub 10 in its passage to the bobbin 11 which is mounted on the spindle 12 so as to rotate therewith. The bobbin, 75 which may be of a well known construction and provided with an enlarged cone-shape end 13, see Fig. 2, has frictional relation with the spindle so as to rotate with the spindle. The spindle 12 is mounted at one end in a 80 projecting lug or lip 14 which is preferably made integral with the end member or plate 15 which constitutes a portion of the frame of the winding mechanism. The lip or lug 14 is preferably arranged at an inclination, 85 as more clearly shown in dotted lines in Fig. 1, so that the end which receives the end of the spindle, and therefore is provided with a spindle-receiving opening, will be disposed at a distance removed from the plate 90 or frame-portion 15. The lip 14, however, extends inwardly from the frame-portion 15 just sufficient to provide secure support for the end of spindle 12 when the latter is in normal position shown in Figs. 1 and 2; the 95 normal position being maintained by yielding means later described, which permits the spindle to be moved in a longitudinal direction so as to enable the end of the spindle to be withdrawn from the lip and swung laterally, by reason of its mounting later to be described when it is desired to remove the bobbin.

The frame of the winding mechanism is 105 rotatably mounted in suitable brackets or standards 16, 16; and this frame consists of the end plate 15 and the opposite end plate 17, both of which are provided with hubs or projections; the end plate 15 being provided with the hub 10 while the end plate 17 is 110 provided with the hollow hub 18, both of which are intended to be mounted in suit-

able bushings, as shown at 19 and 20, respectively. The end of the hub 10, which extends beyond the standard or bracket 16, is provided with a pulley 21 which is 5 adapted to receive a driving belt from a suitable source of power; the pulley 21, in practice, being adapted to be driven at substantially the same speed as the speed of the twisting head from which the yarn is being 10 received and also in the same direction as said head, in order to maintain the twist in the yarn given thereto by the twisting mechanism.

The end members or plates 15 and 17 are 15 maintained in proper relation with each other by the longitudinal members or rods 22, 22 which are suitably secured to the end plates. The end members or plates 15 and 17 also provide bearings for the ends of 20 two screw-rods 23 and 24 which are rotatably mounted in the end plates. In order to give sufficient rigidity to the frame, the opposite ends of the two end plates 15 and 17 are also shown provided with the longitudinal 25 member or rod 25. The screw-rods 23 and 24 are preferably located intermediate of the vertical planes of the frame members or rods 22, 22 and on the same side of the longitudinal center line; all of the last mentioned rods being suitably spaced apart so 30 as to accommodate the yarn-controlling mechanism later to be described. One end of each screw-rod is shown extending through the end plate 17; and the end of 35 screw-rod 23 shown provided with a pinion 26 arranged in mesh with a pinion 27 secured to the end of screw-rod 24. The screw-rod is also provided with a belt-receiving pulley 28. With the screw-rods operatively connected with each other by 40 means of the pinions 26 and 27, it is evident that the rods will rotate in unison but in opposite directions. The pulley 28 is disposed in alinement with a "dead" pulley 29 arranged on the end of bushing 20 disposed 45 about the hub 18. Pulley 28 and "dead" pulley 29 are intended to be operatively connected by means of a suitable belt, indicated at 30, whereby rotation is imparted to the screw-rod 24 when the mechanism is in 50 operation, namely when the spindle-carrying frame is rotated by means of the power imparted to pulley 21, thus causing pulley 28 to be moved through an orbit about "dead" 55 pulley 29.

Spindle 12 is pivotally secured at 31 to an extension or trunnion 32 which passes through the hub 18. The hub 18 is shown counterbored to receive the end of a coil 60 spring 33 which encircles the extension or trunnion 32 and bears against the end portion or head 34 formed on the inner end of extension 32. The spring 33 tends to press the spindle, with the bobbin, toward the 65 right in Figs. 1 and 2 and yieldingly main-

tain the opposite end of the spindle 12 in the opening formed in the lug or lip 14 at the yarn-receiving end of the winding frame.

The extension 32 of the spindle passes entirely through the hub 18 and is provided with a pulley 35 which is preferably loosely mounted thereon. The extension 32 is shown reduced at the outer end so as to provide a shoulder against which pulley 35 bears and has frictional relation therewith; the frictional relation being controlled and maintained by means of a coil-spring 36 which encircles the reduced end of extension 32. The tension of the spring 36 is controlled by a nut 37 which screws onto the threaded end of the extension 32. Pulley 35 is intended to receive a belt, indicated at 38, which is adapted to be driven from a suitable pulley on a countershaft located in 35 the lower part of the frame, but not shown; the belt 38 being arranged to rotate the extension 32, and therefore the spindle 12 in the same direction as the spindle-carrying frame is driven by means of a belt passed 40 about pulley 21. The bobbin-holding spindle, in practice, is rotated at a faster speed than the carrying frame in order to wind the yarn on the bobbin.

Slidably mounted on the two connecting 45 rods 22, 22, which are arranged on the same side of the longitudinal center line of the carrying-frame, is a traveling threader or guide, comprising a block or member 39, which is also provided with openings extending transversely therethrough for the passage of the two screw-rods 23 and 24. These openings are sufficiently large to prevent actual contact between the block and the screw-rods, thus permitting the screw-rods to rotate without in any way affecting the position of the block or member 39. The block or member 39 is provided with a transversely disposed slot of a depth slightly 50 beyond the point where the screw-rods 23 and 24 pass through the block, as indicated at 40 in Figs. 3 and 4; and this slot is adapted to receive the screw-rod engaging members 41 and 42, respectively. The screw-rod 55 engaging members 41 and 42 are identical in construction, but oppositely disposed; each being provided with a bayonet-slot formation, as more clearly shown in Fig. 6, with one end of the slot made arcuate, as 60 shown in Fig. 6, and threaded or provided with a screw-thread engaging portion 43 adapted to engage with the threads of the respective screw-rods. The screw-rod engaging means preferably comprises the two members 41 and 42 shown, which are adapted to slide transversely of the block or head 39 in a slot-way 40, which enables them to be moved into and out of operative relation with their respective screw-rods; in other 65 words, when the blocks are moved trans-

versely of the slot 40, so as to bring the end portion 44 of a member into close relation with the adjacent screw-rod, the element or member 41, or 42 as the case may be, will be 5 out of operative relation with its respective screw-rod. Each member 41 or 42 is provided with an upwardly disposed trunnion 45, more clearly shown in Fig. 6, which is adapted to receive the end of the toggle- 10 lever mechanism now to be described.

The toggle-lever mechanism just referred to is preferably secured on the upper surface of the block or member 39 and, in the particular exemplification, comprises a link 15 46 pivoted at one end to trunnion 45 of member 41, while the other end of the link 46 is pivotally secured to the ends of links 47 and 48. Link 47, in turn, is pivotally secured to a member or lever 49 which is pivoted at 50 on the block or head 39; the pivotal point 50 being at an intermediate point between the ends of member or lever 49; with the pivotal point of link 47 arranged at one end of the lever and therefore to one 25 side of the pivotal point 50, as clearly shown in Fig. 3. Pivotally secured to the trunnion 45 of member 42 is a link 51, the opposite end whereof is pivotally secured to links 52 and 53. Links 52 and 48 have their 30 adjacent ends pivoted on a pin or projection 54 formed on the block or head 39 so as to provide a fixed pivotal point; while link 53 is pivotally secured to the member or lever 49 on the opposite side of pivotal point 50 35 from that where the pivotal point of link 47 is located.

As is evident from the construction shown and described, when lever 49 is oscillated about its pivotal point 50, it will 40 actuate the double toggle-lever mechanism which has operative relation with the elements or screw-rod engaging members 41 and 42. As shown in Fig. 7, the screw-rod engaging portions of the sliding members 45 41 and 42 are arranged at the outer ends and therefore adjacent opposite sides of the head or block 39, so that it will require a movement of the sliding members toward the longitudinal center line of the block or head 50 39 to bring the members into operative engagement with their respective screw-rods.

With this arrangement therefore, it is apparent that when the free or outer end of member or lever 49 is swung to the left, as 55 shown in Fig. 3, link 53 will induce a contracting movement of links 51 and 52, due to the fixed pivotal point 54 at the end of link 52. This will cause member 42 to be moved along the slot-way 40 in the head 39 60 so as to bring its screw-engaging portion 43 into threaded or operative relation with its adjacent screw-rod 24. During this operation, the opposite end of member or lever 49, through the medium of link 47, will force 65 links 46 and 48 into a distended relation,

namely substantially into alignment with each other, as shown in Fig. 3, because of the fixed pivotal point 54 at the end of link 48, thereby forcing member 41 toward the side of head or member 39, namely with the 70 inturned end 44 of member 41 into close proximity with the screw-rod 23, and therefore with the screw-rod engaging portion 43 of member 41 out of operative relation with its screw-rod 23, as shown in Fig. 7. 75

It is evident from this construction and operation, that the head 39, with the mechanisms mounted thereon, will be forced to travel in the direction of rotation of screw-rod 24, or rather, to follow the lead of the 80 screw-threads. In order to induce movement of the head 39 in the opposite direction, it will be necessary to swing member or lever 49 toward the right in Fig. 3, and thereby induce member 41 to be drawn inwardly and into operative engagement with its screw-rod 23, at which time member 42 will be forced out of operative relation with its screw-rod 24. With this situation, the 85 block 39 and elements carried thereby will 90 be forced to travel in the direction of rotation or lead of the threads of screw-rod 23.

The outer end of member or lever 49 is shown slotted or bifurcated so as to provide the two separated projecting portions or 95 prongs 55 and 56.

Pivotedly mounted on the lower side of the block 39 is a yoke member 57 arranged transversely of the block 39 and provided at an intermediate point with a roller 58. 100 The ends of the yoke are trunnioned on the block 39 at the point 59, and one of the ends arranged to extend about the side of the block 39 and given the spider formation or widely separated bifurcations shown at 105 60 in Fig. 4 disposed parallel with the side of the block 39. Pivotally secured at 61 to the spider or bifurcated end 60 of the yoke 57, namely at a point in alignment with the pivotal point 59, is an arm 62 which is 110 adapted to extend intermediate of the projecting portions 55 and 56 of lever 49. Disposed on opposite sides of arm 62 and intermediate of the bifurcations or spider 60, I provide a pair of springs preferably in the 115 nature of coil-springs 63 and 64 adapted to bear against opposite sides of arms 62, while the other ends of the springs bear against the arms of the bifurcations or spider 60; the springs 63 and 64 being of substantially 120 equal tension and exerting pressure in opposite directions against arm 62, so that arm 62 will normally be held at an intermediate point between the bifurcations 60. The 125 springs 63 and 64 are maintained in place by the arcuate guide-rod 65 which is adapted to pass through arm 62 and be secured to the bifurcations 60; the arm 62 being arranged to have free sliding movement on the guide element or rod 65. It is evident from the 130

construction shown and described that arm 62 will be caused to constantly oscillate with yoke 57; such action or tendency maintaining while the pressure of both springs 63 and 64 remains substantially equal; compression of either spring 63 or 64 being induced by momentarily arresting arm 62 in its oscillatory movement by means later to be described.

10 The yoke 57 is maintained under spring pressure by means of a spring 69, one end whereof may be seated in a suitable socket or pocket arranged in the under side of block 39, or secured in place in any suitable 15 manner, while the other end is seated in a socket or secured in place at an intermediate point on yoke 57, see Figs. 4 and 5; the spring 69 normally tending to maintain the roller 58, secured to yoke 57, in contact 20 with the bobbin 11 mounted on the spindle 12 and therefore in contact with the yarn or thread which is being wound on the bobbin.

Secured to the block or head 39 is a yarn-guiding member 66, which is shown formed 25 in the nature of a wire, bent as shown in Fig. 3, and held against movement by any suitable means, as for example by the head of a stud-bolt or screw 67. The member 66 comprises a downwardly disposed portion, 30 see Fig. 2, which terminates in a turn or coil so as to provide an eye through which the yarn is threaded in its passage from the hollow hub 10 to the point where it is being wound on the bobbin. The other end 35 of member 66 is shown bent at an angle and disposed parallel with the side of the block or member 39 so as to extend across the free end of lever 49 to a point intermediate of the bifurcations 55 and 56. This 40 end of the member 66 terminates in a right angularly disposed portion, as shown at 66^a in Fig. 3, and is adapted to extend into the path of the point or tip of arm 62, see Figs. 3, 4 and 7. The tip or end of arm 62 is 45 preferably tapered, as shown, so as to enable it to slip past the end 66^a when the arm has been put under sufficient pressure through the compression of either one of the springs 63 or 64. It is apparent that in 50 arresting the oscillation of arm 62, the spring rearward of the arm, relative to the direction of oscillation, will be compressed by the continued oscillation of bifurcation 60 of the yoke and arm 62 placed under 55 considerable pressure, so that when the arm finally slips past the projection 66^a, it will come into forcible contact with one of the bifurcations of lever 49 and induce positive and complete oscillation thereof and therefore insure complete operation of toggle-lever mechanism and, in turn, of members 41 and 42.

60 In practice, the yarn, or thread, is started on the bobbin 11 at the base of the cone- 65 portion 13; the guiding mechanism having

been moved along the guide-rods 22, 22 of the frame into proximity with the base of the cone, so that member 66 will be substantially in alinement with the point where the yarn is to be placed on the bobbin. The 70 roller 58, carried by yoke 57, and the eye-end of member 66 are arranged in juxtaposition, so that roller 58 will therefore be on the enlarged or cone-portion of the bobbin. The elevation of the yoke 57 induced by 75 roller 58 being placed on the cone-portion of the bobbin will permit a small quantity of yarn to wind on the bobbin before the tripping mechanism of the yarn-guiding head is actuated. The increasing diameter 80 of the bobbin caused by the yarn being wound thereon, further elevates yoke 57 against the action of spring 69 and causes the arm 62 to oscillate until it reaches point 66^a. This operation also causes the bifurcated end 60 of the yoke to the left of arm 62 in Fig. 4 to compress spring 64 against the side of arm 62; the latter being momentarily held against oscillation by the end 66^a of member 66. This holding relation 90 will maintain until the amount of yarn on the bobbin has increased to an extent where the tension of spring 64 is such that arm 62 will be caused to slip past end 66^a and forced into engagement with projection 95 56 of lever 49, which causes the latter to oscillate about its pivotal point 50 in a direction which induces link 53 to distend links 51 and 52 while link 47 will induce links 46 and 48 to be moved into a contracted relation. Such movement of links 51 and 52 will force member 42 out of operative relation with screw-rod 24, while member 41 will be drawn into operative relation with screw-rod 23. As screw-rod 23, in the particular exemplification, rotates in the opposite direction from screw-rod 24, the guiding mechanism or head 39, with its correlated parts, will be caused to travel in the direction or lead of the threads on rod 23, 100 105 namely toward the opposite or reduced end of the bobbin.

As the guiding mechanism travels toward the opposite or reduced end of the bobbin, it is evident that the yoke 57 will be gradually tilted or moved downwardly through the action of spring 69 which maintains roller 58 in contact with the yarn; and such downward movement will gradually oscillate arm 62 in a direction opposite to that previously described until the arm is arrested by projection 66^a, which will place the spring 63 under tension. This condition will maintain until the spring 63 is under sufficient tension to cause the pressure exerted thereby to force arm 62 past the detent 66^a. Such movement will cause arm 62 to strike bifurcation 55, thereby oscillating lever 49 into the position shown in Fig. 3, at which time the mechanism will have forced 110 115 120 125 130

member 41 out of operative relation with screw-rod 23, while member 42 has been drawn into operative relation with screw-rod 24. With this relation of the various parts, the guiding mechanism or head 39 will be caused to move in a direction opposite to that induced through the operation of screw-rod 23, because of the opposite direction of rotation of screw-rod 24, namely 10 toward the cone-end of the bobbin and therefore toward the end of the bobbin provided with the greater amount of yarn. This relation and operation will continue until yoke 57 has been elevated to a degree 15 where spring 64 has been so compressed that the pressure exerted on arm 62 is sufficient to overcome the effect of detent 66^a, when the arm 62 will again be forced into engagement with projection 56 of lever 49 20 thereby causing the lever 49 to oscillate so as to operate the toggle-lever mechanisms in the manner first described, namely where member 42 is moved out of operative relation with screw-rod 24 and member 41 is 25 drawn into operative relation with screw-rod 23.

As is evident from the foregoing description and the drawings, the maximum high and maximum low points for the roller 58, 30 and therefore for the free end of yoke 57, will constantly be advanced toward the reduced or smaller end of the bobbin as the amount of yarn on the bobbin increases, until the opposite or small end of the bobbin 35 has been reached and filled; the yarn or thread, as is evident from this operation will therefore be wound in overlapping stages throughout the length of the bobbin.

It is apparent that the speed of the bobbin 40 will have to vary and be commensurate with the diameter of the portion at which the yarn is being wound, in order to take up the yarn as it is fed to the winding mechanism. To compensate for the difference in 45 diameter, or, in other words, the difference in speed necessary to continuously take up the yarn, I show the pulley 35 loosely mounted on the end of the spindle extension 32, with the pulley 35 maintained in frictional contact with the shoulder formed on the spindle extension 32 by means of the 50 spring 63, as previously described. The tension of spring 36 is regulated by the nut 37 so as to firmly press the pulley 35 into frictional engagement with the shoulder of the extension 32. As the yarn is delivered 55 from the twisting head or mechanism to the winding mechanism at a given speed, it is evident that greater tension or draft will 60 be exerted on the bobbin as the amount of yarn increases thereon and therefore the circumference is increased; and this increased tension or pull will cause slight slippage between the shoulder on the extension 32 65 of the bobbin-holding spindle and the pulley

35, so that the "take-up" of the bobbin will at all times be commensurate with the tension of the yarn and therefore of the feed of the twisted yarn thereto.

Rotation of the frame mechanism, induced by the belt which takes about pulley 21, will swing pulley 28 through an orbit or circle disposed about "dead" pulley 29, which will cause belt 30 to impart rotation to screw-rod 24, and through the medium of 75 pinions 27 and 26 to screw-rod 23, as previously described.

The block or head 39 is preferably provided with a cover-plate, as shown at 68, whereby the toggle-lever mechanisms are 80 inclosed and a comparatively smooth surface provided so as to prevent the yarn or thread coming in contact with and adhering to the operating mechanism.

The construction shown and described, I 85 believe to be the simplest embodiment of the invention, but certain modifications may be made without, however, departing from the spirit of my invention as expressed in the claims.

What I claim is:—

1. A machine of the class described, comprising a longitudinal frame rotatably mounted, a bobbin-carrying spindle arranged in the frame along the axial line 95 thereof, means whereby the frame and said spindle are independently rotated, a pair of screw rods rotatably mounted in said frame and disposed parallel with the spindle, yarn-guiding means slidably mounted on said frame so as to travel in a direction lengthwise of the bobbin, said yarn-guiding means comprising a pair of screw-rod engaging members adapted to move transversely of 100 said frame into and out of engagement with the adjacent screw-rod, and controlling mechanism adapted to be actuated by the quantity of yarn wound on the bobbin whereby the selective screw-rod engaging member 105 is actuated.

2. A winding machine of the class described, comprising a revoluble frame, a bobbin-carrying spindle revolvably mounted at the axial line of said frame, means whereby the frame and said spindle are independently rotated, yarn-guiding means slidably mounted on the frame so as to travel lengthwise of the bobbin on the spindle, a pair of rotatably mounted screw-rods disposed 115 through said means, screw-rod engaging means disposed transversely of the second mentioned means and adapted to alternately be moved into operative engagement with the selective screw-rod, and tripper mechanism adapted to be controlled by the quantity of yarn on the bobbin whereby said last mentioned means is actuated.

3. A machine of the class described, comprising a rotatably mounted frame, a bobbin-carrying spindle rotatably mounted at 130

- the axial line within said frame, means whereby the frame and spindle are independently rotated, a pair of screw-rods extending lengthwise of the frame and adapted to rotate in unison when said frame is revolved, a member slidably mounted on said frame so as to travel lengthwise thereof, said member being adapted to guide the yarn, means disposed transversely of said member and of said screw-rods and adapted to alternately engage with said screw-rods so as to transmit movement to said member in the direction of the lead of the screw-threads of said screw-rods, means pivotally mounted on said member and in operative engagement with said second mentioned means, and tripping mechanism carried by said member and adapted to actuate said third mentioned means, said tripper mechanism including a spring-controlled element in yielding traveling relation with the bobbin whereby the quantity of yarn wound on the bobbin will cause said spring-controlled element to actuate said tripping mechanism.
4. A machine of the class described, comprising a revoluble frame, a bobbin-carrying spindle extending lengthwise of the frame and revolvably mounted at the axial line thereof, a member slidably mounted on the frame so as to move lengthwise of the bobbin-carrying spindle, a yarn-guiding element secured to said member, spring-controlled means pivotally mounted on said member and adapted to be in constant contact with the bobbin or yarn wound thereon, means disposed lengthwise of the frame and rotatably mounted therein, means carried by said member and adapted to move transversely of said second mentioned means, and means intermediate of said spring-controlled means and said third mentioned means whereby the latter is forced into operative engagement with the selective portion of said second mentioned means by the quantity of yarn wound on the bobbin.
5. A machine of the class described, comprising an elongated revoluble frame, a bobbin-carrying spindle mounted in said frame and independently revoluble, a member slidably mounted on said frame so as to travel lengthwise of the spindle, said member being adapted to guide the yarn onto the bobbin, a pair of screw-rods disposed lengthwise of the frame and adapted to be rotated through the rotation of said frame, means slidably mounted on said member and adapted to move transversely of said screw-rods, and means intermediate of the bobbin and said first means adapted to be controlled by the quantity of yarn wound on the bobbin, said second means being adapted to move the first means into operative engagement with the selective screw-rod.
6. A machine of the class described, comprising a revolvably mounted elongated frame, a bobbin-carrying spindle rotatably mounted in said frame, means whereby the frame and said spindle are independently rotated, a pair of screw-rods disposed lengthwise of the frame and adapted to rotate through the rotation of said frame, guiding means slidably mounted on said frame, means carried by the second mentioned means, adapted to be controlled by the quantity of yarn wound on the bobbin, and means intermediate of the third mentioned means and the second mentioned means, a portion whereof is adapted to move transversely of the screw-rods and provide operative relation between the second mentioned means and the selective screw-rod through the positioning of the third mentioned means.
7. A machine of the class described, comprising an elongated revoluble frame, a bobbin-carrying spindle rotatably mounted in said frame, means whereby the frame and said spindle are independently operated, a member slidably mounted on the frame so as to move lengthwise of the spindle, said member being adapted to guide the yarn toward the bobbin on the spindle, means carried by said member and adapted to be in traveling contact with the bobbin, rotating means carried by the frame and adapted to be operated through the rotation of said frame, means carried by said member adapted to move transversely of and into operative relation with said rotating means, and means intermediate of said second mentioned means and said fourth mentioned means whereby the last means are actuated through the positioning of said second mentioned means.
8. A machine of the class described, comprising a frame provided with hollow trunnions at opposite ends thereof whereby said frame is rotatably mounted, a bobbin-carrying spindle rotatably mounted in said trunnions, means whereby the frame and said spindle are independently rotated, a pair of screw-rods rotatably mounted in said frame and disposed lengthwise of the spindle, means intermediate of the frame and said screw-rod whereby the latter are rotated when said frame is revolved, a yarn-guiding member slidably mounted on the frame so as to move lengthwise of the spindle, a spring-controlled member carried by said yarn-guiding member and arranged in traveling contact with the bobbin, means carried by said yarn-guiding member, a portion whereof is adapted to alternately move into operative relation with both of said screw-rods, and spring-controlled means in operative engagement with said spring-controlled member and adapted to actuate said third mentioned means so as to move said portion thereof into operative engagement with the selective screw-rod.

through the positioning of said spring-controlled member by the quantity of yarn wound on the bobbin.

9. A machine of the class described, comprising an elongated frame rotatably mounted, a bobbin-carrying spindle rotatably mounted in the frame at the axial line thereof, means whereby the frame and the spindle are independently rotated, a yarn-guiding member slidably mounted on the frame so as to move in a direction lengthwise of the spindle, a pair of screw-rods rotatably mounted in the frame and disposed through said member, means intermediate of the screw-rods and said frame whereby the screw-rods are rotated when the frame is revolved, screw-rod engaging members slidably mounted on said yarn-guiding member, a spring-controlled element carried by the yarn-guiding member and adapted to be in traveling contact with the bobbin, and tripping mechanism intermediate of said screw-rod engaging members and said spring-controlled element whereby the selective screw-rod engaging member is actuated through the positioning of the spring-controlled element by the quantity of yarn wound on the bobbin.

10. A machine of the class described, comprising a revolvably mounted elongated frame, a bobbin-carrying spindle rotatably mounted in the frame, means whereby the frame and spindle are independently rotated, a yarn-guiding member slidably mounted on the frame so as to travel in a direction lengthwise of the spindle, a pair of screw-rods revolvably mounted in the frame, means whereby the screw-rods are rotated when said frame is revolved, a pair of screw-rod engaging members slidably mounted on said yarn-guiding member, a spring-controlled element carried by the yarn-guiding member and adapted to be in traveling contact with the bobbin on the spindle, and toggle-lever mechanism intermediate of the screw-rod engaging members and the spring-controlled element whereby the selective screw-rod engaging member is brought into operative engagement with its screw-rod through the positioning of the spring-controlled element by the quantity of yarn wound on the bobbin.

11. A machine of the class described, comprising an elongated revolvably mounted frame, a bobbin-carrying spindle rotatably mounted in said frame, means whereby the frame and spindle are independently rotated, yarn-guiding means slidably mounted on the frame so as to move in a direction lengthwise of the spindle, a member pivotally mounted on said yarn-guiding means and adapted to be in traveling contact with the bobbin on the spindle, rotating means carried by the frame and adapted to be operated through the rotation of said frame,

means carried by the yarn-guiding means and movable transversely of said rotating means and adapted to alternately have operative engagement with selective portions of the rotating means, and mechanism intermediate of the pivotally mounted member and said last mentioned means whereby the latter is actuated.

12. A machine of the class described, comprising an elongated frame provided with hollow trunnions whereby the frame is revolvably mounted, a bobbin-carrying spindle rotatably mounted in said trunnions, means whereby the frame and said spindle are independently rotated, a yarn-guiding member carried by the frame so as to move lengthwise thereof, a pivoted member mounted on the yarn-guiding member and arranged to have traveling contact with the bobbin, a pair of rotating members disposed lengthwise of the frame, means carried by the yarn-guiding member, disposed transversely of said pair of rotating members and adapted to be alternately moved into operative engagement with the selective member of said pair of members, and spring-controlled toggle mechanisms intermediate of said second mentioned member and said last mentioned means whereby the latter is adapted to be actuated through the positioning of said second mentioned member.

13. A machine of the class described, comprising an elongated frame, a bobbin-carrying spindle mounted in said frame, a yarn-guiding member carried by the frame so as to move lengthwise of the bobbin on the spindle, a pair of screw-rods rotatably mounted in the frame, screw-rod engaging means, lever mechanism mounted on the yarn-guiding member and adapted to control said screw-rod engaging means, and spring-controlled trigger mechanism carried by the yarn-guiding member and adapted to actuate said lever mechanism, said trigger mechanism being adapted to be controlled by the quantity of yarn wound on the bobbin.

14. A machine of the class described, comprising an elongated frame, a bobbin-carrying spindle mounted in said frame and disposed lengthwise thereof, a yarn-guiding element mounted on the frame so as to travel lengthwise of the spindle, a pair of screw-rods rotatably mounted in the frame, means adapted to move transversely of the screw-rods and arranged to alternately have operative engagement with the selective screw-rod, lever mechanism pivotally mounted on the yarn-guiding element and arranged to control said means, and spring-controlled trigger mechanism pivotally mounted on said yarn-guiding element and adapted to actuate said lever mechanism, a portion of said trigger mechanism being adapted to be in traveling contact with the bobbin.

15. A machine of the class described, comprising an elongated frame, a bobbin-carrying spindle disposed lengthwise of the frame, a yarn-guiding element slidably mounted on the frame so as to move lengthwise of the spindle, a pair of screw-rods rotatably mounted in the frame, screw-rod engaging means carried by the yarn-guiding element and movable transversely of the screw-rods so as to alternately be brought into operative engagement with the selective screw-rod, lever mechanism pivotally mounted on said element and arranged to control said means, a spring-controlled member pivotally mounted on said element and arranged in traveling contact with the bobbin on said spindle, and trigger mechanism intermediate of said last member and said lever mechanism whereby the latter may be actuated.
16. A machine of the class described, comprising an elongated frame, a bobbin-carrying spindle disposed lengthwise of the frame, a yarn-guiding element slidably mounted on the frame so as to move lengthwise of the spindle, a pair of screw-rods rotatably mounted in the frame, screw-rod engaging means carried by the yarn-guiding element and adapted to alternately be brought into operative engagement with the selective screw-rod, toggle-lever mechanism pivotally mounted on said element and in operative engagement with said screw-rod engaging means, spring-controlled trigger mechanism pivotally mounted on said element and in operative relation with the toggle-lever mechanism, and a pivotally mounted member carried by said element and adapted to control said trigger mechanism, said last mentioned member being adapted to be in constant traveling contact with the bobbin on the spindle and be affected by the quantity of yarn wound on the bobbin.
17. A machine of the class described, comprising an elongated frame, a bobbin-carrying spindle rotatably mounted in the frame, a yarn-guiding element slidably mounted on the frame so as to travel lengthwise of the spindle, a pair of rotatably mounted screw-rods disposed lengthwise of the frame, screw-rod engaging means carried by the yarn-guiding element adapted to alternately have operative engagement with said screw-rods, toggle-lever mechanism pivotally mounted on the yarn-guiding element and adapted to control the screw-rod engaging means, a spring-controlled member pivotally mounted on said yarn-guiding element and arranged in traveling contact with the bobbin on the spindle, a spring-controlled arm operatively connected with said spring-controlled member and adapted to have operative relation with said toggle-lever mechanism, and tripping mechanism whereby said arm is controlled.
18. A machine of the class described, comprising a rotatably mounted frame, a bobbin-carrying spindle rotatably mounted in said frame, a member slidably mounted on the frame adapted to travel lengthwise of the spindle, a pair of screw-rods rotatably mounted in the frame and disposed lengthwise of the spindle, a member pivotally mounted on the first mentioned member and arranged in traveling contact with the bobbin on the spindle, a pair of members slidably mounted on the first mentioned member and adapted to alternately have operative relation with said screw-rods, toggle-lever mechanism pivotally mounted on the first mentioned member and operatively connected with said last mentioned pair of members, and spring-actuating tripping mechanism arranged intermediate of the second mentioned member and said toggle-lever mechanism whereby the latter will be actuated at predetermined moments through movement of the second mentioned member.
19. A machine of the class described, comprising a rotatably mounted frame, a bobbin-carrying spindle rotatably mounted in said frame, means adapted to travel lengthwise of the frame and to guide the yarn onto the bobbin, mechanism disposed intermediate of said means and the bobbin and arranged in traveling contact with the latter so as to be positioned by the quantity of yarn wound on the bobbin, rotating means disposed lengthwise of the frame, means slidably mounted on the first mentioned means and arranged to engage with selective portions of said rotating means, toggle-lever mechanism whereby the last mentioned slidably mounted means are controlled, and actuating means intermediate of the first mentioned mechanism and said toggle-lever mechanism whereby the latter is controlled.
20. A machine of the class described, comprising an elongated frame, a bobbin-carrying spindle rotatably mounted in the frame and disposed lengthwise thereof, a yarn-guiding element slidably mounted on the frame so as to travel lengthwise of the bobbin on the spindle, rotating means carried by the frame and disposed lengthwise of the spindle, mechanism carried by the yarn-guiding element and adapted to alternately have operative engagement with selective portions of said rotating means, a spring-controlled element carried by the first mentioned element and arranged in traveling contact with the bobbin on the spindle, toggle-lever mechanism carried by the said first mentioned element and arranged intermediate of said first mentioned mechanism and said spring-controlled element whereby the first mentioned mechanism is actuated through the positioning of said spring-controlled element, and a detent carried by said yarn-guiding element whereby the moment of operation of the tog-

gle-lever mechanism through the positioning of said spring-controlled element is determined.

21. A machine of the class described, comprising an elongated frame, a bobbin-carrying spindle disposed lengthwise of the frame, means whereby the frame and spindle are independently rotated, a yarn-guiding element slidably mounted on the frame so as to move lengthwise of the spindle, a pair of screw-rods rotatably mounted in the frame and disposed lengthwise thereof, means intermediate of the axis of the frame and said screw-rods whereby the latter are rotated when said frame is revolved, a pair of members slidably mounted on the yarn-guiding element and adapted to alternately engage with the screw-rod disposed adjacent thereto, toggle-lever mechanisms carried by said yarn-guiding element and arranged to control said slidably mounted members, a pivoted lever whereby said toggle-lever mechanisms are simultaneously actuated, a spring-controlled member pivotally mounted on said element and arranged in traveling contact with the bobbin, a pivoted member intermediate of said spring-controlled member and said lever, said last-mentioned member having a yielding relation with the member in traveling contact with the bobbin, and a detent whereby said last mentioned member is momentarily arrested and placed under spring pressure until the bobbin-contacting member approaches the maximum points in its raised and lowered positions.
22. A machine of the class described, comprising an elongated rotatable frame provided with hollow trunnions at the ends thereof, a bobbin-carrying spindle rotatably mounted in said trunnions, means whereby the frame and spindle are independently rotated, a pair of screw-rods rotatably mounted in the frame and disposed lengthwise thereof, means intermediate of one of the trunnions of the frame and said screw-rods whereby the latter are rotated when said frame is revolved, a yarn-guiding element slidably mounted on the frame so as to move lengthwise of said screw-rods, means intermediate of said element and the bobbin on the spindle, arranged in traveling contact with said bobbin and adapted to be positioned by the yarn wound on the bobbin, screw-rod engaging means slidably mounted on said element and adapted to alternately move into operative engagement with each screw-rod whereby the direction of movement of the yarn-guiding element is determined, toggle-lever mechanism carried by said yarn-guiding element and arranged to control the screw-rod engaging means, means intermediate of said toggle-lever mechanism and said bobbin-contacting means whereby the toggle-lever mechanism is actuated, and tripping mechanism carried by the yarn-guiding element whereby the moment of operation of said last-mentioned means is arrested until said bobbin-contacting means reaches the maximum points, approximately, in the raised and lowered positions thereof.
